UNITED STATES PATENT OFFICE.

FRANK H. BOLTE, OF MILWAUKEE, WISCONSIN, ASSIGNOR TO THE EGELHOFF MANUFACTURING COMPANY, OF SAME PLACE.

HORSE HAY-FORK.

SPECIFICATION forming part of Letters Patent No. 307,906, dated November 11, 1884.

Application filed May 16, 1884. (No model.)

To all whom it may concern:

Be it known that I, FRANK H. BOLTE, of Milwaukee, in the county of Milwaukee, and in the State of Wisconsin, have invented certain new and useful Improvements in Hay-Forks; and I do hereby declare that the following is a full, clear, and exact description thereof.

My invention relates to improvements in hay-forks, and will be fully described hereinafter.

In the drawings, Figure 1 is a perspective view of my improved device. Fig. 2 is a vertical section of the broken upper part of the same, showing the fork when locked for hoisting; and Fig. 3 is a like section of the same, showing the fork locked for loading.

The object of my invention is to simplify the locking mechanism of that class of hay-forks known as "harpoon-forks," and thereby considerably reduce the cost of manufacture and render the operation of the fork more effective and its working parts less liable to get out of order.

A is the sheath of the fork, and B the sliding rod, to the lower end of which are attached the retaining-tines b b. The upper ends of the side bars of the sheath are provided with ears a' a' a'' a'', projecting outward and perforated to receive the connecting-pins a'' a'', both ends of which are riveted against the outer faces of said ears, while the inner faces of the ears rest against shoulders upon said pins. Hinged on the pin a'', between the ears a'' a'' of the side bars of the sheath, is the locking-lever C. The hinged end of this lever has flat-faced shoulders c c', formed on the opposite sides, which shoulders are designed to lock the fork in the positions required either for piercing the hay or for locking the tines when loaded by bringing one or the other in close contact with the adjoining face of the sliding rod B. For that purpose the opposite face of this rod

has the semicircular notches b' b'', in one of which fits half of the pin a'' as the sliding rod B is acted upon by one or the other of the shoulders c c' of the locking-lever C. In the position represented in Fig. 3 the shoulder c is in contact with the rod, holding the notch b'' in engagement with the pin a'', thus locking it in place prior to its introduction into the hay. In the position shown in Fig. 2 the shoulder c' is in contact with the rod, with the notch b' engaging the pin a''. A stop, b'', is formed in the notched face of the sliding rod B, just below the notch b'', to prevent said rod from sliding too far out of the sheath.

Having thus described my invention, what I claim as new, and desire to secure by Letters Patent, is—

1. In a hay-fork, the combination of the sliding rod B, provided with two notches in its rear edge, the inclosing-sheath A, having its sides connected at the top by two pins, one in front and the other in rear of said rod, and a locking-lever pivoted to the front pin, and having a flat-faced projecting shoulder on each side of its pivoted end, whereby one or the other notch in said rod may be locked in engagement with the rear pin, substantially as set forth.

2. In a hay-fork, in combination with the sheath A, having ears a' a' a'' a'', and connecting-pins a'' a'', the sliding tine-operating rod B, having notches b' b'' and stop b'', and the hinged locking-lever C, having shoulders c c', substantially as and for the purpose set forth.

In testimony that I claim the foregoing I have hereunto set my hand, at Milwaukee, in the county of Milwaukee and State of Wisconsin, in the presence of two witnesses.

FRANK H. BOLTE.
